UNITED STATES PATENT OFFICE.

NATHAN HENRY, OF CHICAGO, ILLINOIS.

TROUSERS.

Application filed August 23, 1924. Serial No. 733,756.

To all whom it may concern:

Be it known that I, NATHAN HENRY, a citizen of the United States, and a resident of the city of Chicago, county of Cook, and State of Illinois, have invented certain new and useful Improvements in Trousers, of which the following is a specification.

My invention relates to new and useful improvements in trousers, and has for an object to provide belt means at the front and sides of the trousers' top, which means is made of flexible material and preferably of a material to match the trousers, which belt means is particularly adapted for drawing the trousers flexibly but firmly together at its top and to support it securely but pliably on the waist, and is constructed for the purpose to doing away with the usual stiff leather belt and the majority of the usual loops for holding the belt. Another object is to provide a belt means on the trousers which cannot be detached and mislaid or lost like the usual belts, and provide such belt means which effect both comfort and economy.

The usual summer trousers are provided with a plurality of loops around the top or waist band and a belt of leather or some stiff material mounted therein. These belts are stiff and unyielding and are detachable and therefore liable to be mislaid and lost causing trouble and inconvenience and are also an added and unnecessary expense in conjunction with the trousers. To overcome such expense and trouble I provide belt means which consists of pliable material and permanently secured to the trousers' band, being therefore particularly adapted on trousers for boys as well as for men, and which belt means is preferably made of material the same or similar to the material of the trousers, thus being provided at a minimum of cost and producing a maximum of economy in producing the complete trousers, with belt, ready for wear.

Other objects will appear hereinafter.

The invention consists in the combinations and arrangements of parts hereinafter described and claimed.

The invention will be best understood by reference to the accompanying drawing forming a part of this specification, and in which.

Fig. 1 is an elevational view of a trousers supplied with my improved flexible belt means;

Figs. 2 and 3 are enlarged vertical sectional views taken respectively on the lines 2-2 and 3-3 of Fig. 1; and

Fig. 4 is an enlarged front view of the belt means with the buckle or fastening means shown thereon partly broken away.

In the form of my invention illustrated in the drawing I have shown a trousers 10 with a top part or waist band 11 which is 65 preferably provided with only 2 of the usual belt holding loops 12 placed at the front of the waist band, and preferably at the front quarter points of the band as shown. This trousers is further provided with a 70 pair of belt means or members 13 and 13' made from pliable material of fabric to match the trousers, preferably from the same material as the trousers, and which members are secured to the trousers' band 75 rearwardly at the sides, and are preferably secured each with one end in the seam 14 at the rear quarter point, rearward of the hip portion of the trousers, and retained by the stitching of said seam 14, as shown, 80 but preferably without said stitching or seam piercing the lining 15. A buckle or fastening member 16 preferably of an anti-rust material is detachably mounted on the belt members, and preferably comprises 85 a clamp means 17 with serrations 18 pressing the belt member 13 against the plate 19 on the buckle 16, and contains a pin or roller 20 which is movably mounted in a slot 21 at the forward end of the buckle 90 for clamping and holding the belt member 13' in position, as shown.

This improved form of pliable belt construction provides comfort and economy and the trousers will be left smooth at the 95 front when the belt is tightened, and the pleats, if any, are readily placed or drawn at the rear of the belt members over the hips.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having described my invention, what I claim as new and desire to secure by Letters Patent is:

1. A trousers having a waist-band with seams at the rear quarter points and a lining across the inside of said seams, a pair of belt members of flexible fabric similar to the material of the trousers, each member having one end stitched into one of said seams at the quarter point rearward of the hip and extending forward therefrom, a pair of loop members at the front of the trousers through which said belt members pass, and means for holding the free ends of said belt members adjustably in position.
2. A trousers having a waist band with seams at the rear quarter points and a lining extending across the inside of said seams,

a pair of belt members of flexible fabric of the trousers' material, each member having one end stitched into one of said seams at the quarter point rearward of the hip and extending forward therefrom, a pair of loop members at the front quarter points of said band to embrace and retain said belt members in proper vertical position, and a buckle member with means for adjustably and releasably holding the free ends of both of said belt members in position. 20 25

In testimony whereof I have signed my name to this specification.

NATHAN HENRY.
